ADJUSTABLE DRAPERY BRACKET

Ruth M. Behrle, Washington, D. C.

Application July 29, 1942, Serial No. 452,766

3 Claims. (Cl. 211—105.3)

(Granted under the act of March 3, 1883, as amended April 30, 1928; 370 O. G. 757)

The invention described herein may be manufactured and used by or for the Government of the United States for governmental purposes without the payment to me of any royalty thereon in accordance with the provisions of the act of April 30, 1928 (ch. 460, 45 Stat. L. 467).

This invention pertains to improvements in supports and more particularly in drapery supporting brackets, the principal purposes of which are to provide supporting strength, ease of installation, simplicity of construction, and adjustability in points of suspension from the frames of windows or doors to accommodate and provide for desired variations in the widths or spacings of draperies.

A further object of the improvement is to provide a drapery support whose points of securement to a window frame are invisible to the normal view, thereby preventing destruction to and defacing marks on the face of the frame by nails and screws.

Another object of the invention is to provide a drapery support which is subjected predominantly to shearing stresses or edgewise bending stresses and in which the securing screws or nails are subjected solely to shearing stresses as distinguished from bending and tensional stresses.

These and other objects of the invention will become apparent from the following specification and appended claims. A preferred embodiment having the characteristics of my invention and by which the same may be practiced is illustrated in the accompanying drawing in which—

Figure 1 is a view in perspective illustrating the improved embodiment applied to a window frame in a manner whereby the draperies may be hung at a width beyond that of the frame;

Figure 2, a top plan view of the Figure 1 application of the support and illustrating in dotted lines the application of the support in a still further extended position; and

Figure 3, a perspective view of the embodiment illustrating its application for a hanging of draperies substantially flush with the edge of the window frame.

The improved support in the illustrated embodiment is formed of a straight length of strap iron given a 90° twist 10 at a point intermediate its ends 11 and 12 to bring the portion between end 11 and the twist on a horizontal plane for securement to the top edge 13 of a window frame 14 and to bring the portion between the end 12 and the twist 10 on a vertical plane for strength purposes described hereinafter. The portion of the stock between end 12 and the twist 10 is

given a 90° bend 15 adjacent the twist and removed from the bend 15 the same portion of the strap of material is again given a 90° bend 16, in the same direction as bend 15, to bring the remaining portion 17, between bend 16 and end 12, back into substantial parallelism with the end portion 18 between the twist 10 and end 11. The length of the arm 19 between bends 15 and 16 should be sufficient to space the drapery supporting arm 17 a desired or suitable distance from the face of the window frame 14 to accommodate drapery folds and hooks outwardly beyond the normal attachments for curtains and shades.

15 The horizontally disposed securing arm portion 19 is provided with a plurality of holes 20 whereby the support may be secured as by a screw 21 driven into the top 13 of the frame 14. The plurality of holes 20 provide adjustability, affording 20 any desired extension of the bracket beyond the width of the frame 14, as shown in Figures 1 and 2, or at a position substantially flush with the edge of the frame, as shown in Figure 3.

To relieve the securing arm 18 of torsional 25 stresses and to relieve screws 21 of bending and tensional stresses, by the hanging weight of drapes on arm 17, I provide a vertical support 22 consisting of a flat piece of similar strap iron stock given a 90° bend 23 whereby the leg end 30 portion 24 may be secured, as by screws 25, vertically to the side 26 of the frame 14 and whereby the horizontally disposed bent end portion 27 may be secured to the under face of the horizontally disposed supporting arm portion 18 by 35 such as bolts 28 through one or more of the holes 20. The usual extension arm 29 may be applied to the arm 17 or in lieu thereof a rod or bar of any conventional type may bridgingly span the space from the arm 17 of one bracket to the other.

By positioning the vertical support 22 in a manner whereby the end portion 27 is disposed outwardly away from the window frame, as disposed in the showing of Figure 1, that portion 45 27 will serve as a support for the portion of the arm 18 which extends beyond the limits of the window frame. When it is desired to hang the drapes flush with the sides of the window frame however, the end portion 27 of the bent support 50 22 should be disposed in a reverse direction, as shown in Figure 3, in order that the supporting arm 19 for the drapery arm 17 may be brought nearer to the plane of the side 26 of the window frame.

By the described structure the principal

stresses upon the support, due to the weight of the drapery, are in shear and in bending only in a direction edgewise of the strap material. Likewise the securing screws 21 and 25 are subjected to shearing stresses predominantly, rather than bending or tensional stresses which in prior art structures tend to loosen the bracket and destroy the holding characteristics of nails or screws. More specifically, an evenly distributed downward pull on the drapery support arm 17 subjects that arm and the spacing arm 19 to edgewise bending and shearing stresses. Likewise the stresses to which the leg 24, of the vertical support 22, is subjected is solely in shear and edgewise bending. Similarly securing arm 18 is subjected to shearing stresses and is relieved of torsional stresses by the bearing of the lower end of the vertical support against the wall adjacent the window frame. By this arrangement it will be seen that screws 21 and 25 will be subjected solely to shearing stresses as distinguished from tension and bending since they are normal to the direction of pull upon arm 18 and leg 24.

In the use of the device, for narrow windows, for instance, the drapes may be hung predominantly over the wall adjacent the side of the window frame, as shown by the application of the device in dotted lines in Figure 2, to give the effect of a wider window. In this manner the lined sides of the drapes are not exposed to view from the outside of the window and the drapes are not exposed to the deteriorating effects of sunlight or to dust, wind and rain when the windows are in open position. Drapes so hung do not obstruct the normal light and view through a window nor will they obstruct the normal flow of air through an open window. Should it be desired to limit the overall width a pair of the drapes to substantially that of a window frame, the supports may be mounted in the manner shown in Figure 3, i. e., by a reversal of the support 22 from the position shown in Figure 1.

The improved type of drapery support is particularly adaptable for the "blacking-out" of windows since to effectively close out lateral light beams it is usually necessary to extend the draperies well out beyond the window frame.

By the described improvements, a strong adjustable drapery support is provided and one which may be readily attached, two screws being sufficient. Furthermore, by the improvements described the exposed faces of the window frames are not marred or destroyed by screw holes since the securing screws are run into the top and upper side edge of the frame where they are practically invisible to normal view.

Having described my invention and illustrated an embodiment by which the same may be practiced, what I claim is:

1. A device adapted to suspend a drape generally parallel to the plane of a window in adjustable overlapping relation with respect to the sides of the window comprising a generally U-

shaped strap member having a generally rectangular cross-section with one leg of the U-shaped member presenting a flat side when viewed normal to the plane of the U defined thereby said flat side being provided with a plurality of spaced apertures therein for accommodating fastening means, and a generally L-shaped strap member having one leg thereof adapted to be fastened to said U-shaped member 5 with the other leg of said L-shaped member extending therefrom normal to the plane of the U defined by said U-shaped member, said L-shaped member being provided with a plurality of apertures therein for accommodating fastening means, whereby the support made up of the U and L shaped members fastened together in predetermined adjustable position may be fastened to the top and side edges of a window frame in predetermined overlapping relation by 10 screws extending through the apertures provided in said U and L shaped members respectively.

2. A drapery support formed of strap-like material of rectangular cross-section having end portions fixed in substantially parallel relationship to one another by an intermediate portion 25 the plane formed by the two greater dimensions of one of said end portions being substantially normal to that of the other end portion whereby one of said end portions may be positioned 30 flatwise on the top surface of a window frame with the other parallel end portion having its maximum lateral dimension extending vertically, said portion adapted to be placed on the top surface of a window being provided with a plurality 35 of apertures therein for accommodating fastening means, and a generally L-shaped strap member having one leg thereof adapted to be fastened to the end portion of said first mentioned member adapted to be positioned flatwise on a 40 window frame, said L-shaped member being provided with a plurality of apertures therein for accommodating fastening means whereby the support made up of said members may be fastened to the top and side edges of a window 45 frame by screws extending through the apertures provided in said members.

3. A drapery support for suspending a drape in adjustable overlapping position with respect to the side of a window formed of strap-like material 50 bent about its axis of least bending moment to form a generally U-shaped member having parallel legs, one leg of which is twisted through an angle of 90 degrees with respect to the other, in combination with an L-shaped strap member 55 bent about its axis of least bending moment, the twisted portion of said U-shaped member and the L-shaped member being provided with a plurality of apertures therein for accommodating fastening means whereby the two said members 60 may be fastened together and the assembly fastened to the top and side edges respectively of a window frame.

RUTH M. BEHRLE.
